UNITED STATES PATENT OFFICE.

HERMAN C. HIRSCHY, OF MINNEAPOLIS, MINNESOTA, ASSIGNOR TO THE HIRSCHY COMPANY, OF MINNEAPOLIS, MINNESOTA, A CORPORATION OF MINNESOTA.

WASHING-MACHINE.

1,349,338.

Specification of Letters Patent. Patented Aug. 10, 1920.

Application filed May 18, 1918, Serial No. 235,370. Renewed July 21, 1919. Serial No. 312,321.

To all whom it may concern:

Be it known that I, HERMAN C. HIRSCHY, a citizen of the United States, resident of Minneapolis, county of Hennepin, State of Minnesota, have invented certain new and useful Improvements in Washing-Machines, of which the following is a specification.

In the operation of a washing machine using a dolly, the clothes agitating device 10 operated either through the bottom or the top of the tub, difficulty has been experienced in preventing the clothes from winding on the sleeve or standard extending up through the bottom of the tub or accumulat- 15 ing in a mass in the center of the tub when the drive of the dolly is from the top, or being caught between the dolly and its hub. Evidently the nearer the clothes are to the center of the tub the less their movement 20 will be and the smaller the degree of agitation and a consequent decrease in efficiency of the machine.

The object, therefore, of my invention is to provide means between the dolly and the 25 bottom of the tub which operates constantly to throw the clothes out toward the walls of the tub into the path of the arms of the dolly and prevent them from winding or twisting around the central standard, or 30 working in between the dolly and its hub or being rolled into a ball in the middle of the tub.

In the accompanying drawings forming part of this specification,

35 Figure 1 is a vertical sectional view through a washing machine tub embodying my invention,

Fig. 2 is a similar view, showing a modified means for operating the dolly.

40 In the drawing, 2 represents the bottom of the washing machine tub, 3 the side walls and 4 the cover therefor. A flanged hub 5 is mounted in the bottom of the tub forming a bushing for the central opening there- 45 in and a sleeve 6 is fitted within said central opening and extends upwardly to a point near the top of the tub and fits within a socket in the hub 7 that is secured to the upper end of a shaft 8 arranged within the 50 sleeve 6 and to which power is applied to drive the hub, and a dolly 9 is slidably mounted thereon. This part of the device is of ordinary construction.

Below the dolly I arrange a deflector or 55 guard 10, shown here as of bell shape con-

struction, though it may be of any other suitable form, resting at its lower end upon the bottom of the tub and having converging walls toward the top, terminating preferably in a head 11 having a socket 12 to 60 receive the lower end of the hub 7 and the dolly may have a recess 13 therein to receive the upper portion of the head 11. This construction may, however, be varied to suit different conditions. The head 11 has the 65 function of keeping the clothes from working into the bearing of the dolly or between the dolly and the guard. The walls of the deflector flare outwardly and downwardly and present a curved surface in the path of 70 the moving clothes and in the revolution of the dolly these clothes, instead of winding around the central shaft, and becoming entangled thereon and interfering with the capacity and efficiency of the machine, will 75 be constantly thrown or worked out away from the center of the tub and kept in the path of the dolly arms so that there will be a constant agitation and movement of the clothes while the dolly is in operation. The 80 walls of the deflector will tend to work the clothes outwardly to a point where they will travel in a longer path and be more thoroughly agitated and will be prevented from becoming snarled or twisted as they frequently are when rolled around the middle 85 of the tub and the driving shaft.

The deflector may be made of wood, metal, or any other suitable material and it may be hollow, as shown, or slatted or with perforations therein, as may seem advisable, all of which constructions I regard as immaterial modifications of the form herein shown.

The flaring shape of the upper end of the 90 guard tends to throw the clothes contacting therewith outwardly and prevent them from working in between the dolly and its hub and being caught and torn thereby. I thus provide means which will not only work 95 the clothes away from the center of the tub to a point of maximum travel, but also protect them from damage during the washing operation.

In Fig. 2 the driving shaft 14 depends 100 through the top of the tub and has a hub 15 secured thereon supporting the dolly, as de- 105 scribed, while the deflector 16, also bell-shaped, has its opening extending entirely therethrough, the lower end of the hub 15 110

fitting within the open upper end of the deflector. The upper end of the deflector in both cases is flared sufficiently, as in Fig. 1, to throw the clothes out, away from the center of the tub and into the path of the revolving dolly arms.

The function of the deflector shown in Fig. 2 is substantially the same as the one described with reference to Fig. 1, its curved flaring walls operating to throw the clothes outwardly away from the center of the tub and the result will be a more efficient washing and all danger of the clothes winding up or accumulating in the center of the tub, or working into the hub of the dolly, will be positively prevented.

I claim as my invention:

1. The combination, with a washing machine tub and its dolly and a drive shaft for said dolly projecting upwardly through the bottom of the tub, of a guard interposed between said dolly and the bottom of the tub and having a head at its upper end provided with a surface for directing the clothes outwardly and downwardly away from the bearing between the dolly and guard, the walls of said guard flaring outwardly and downwardly from said head to direct the clothes toward the walls of the tub and into the path of the dolly arms.

2. The combination, with a washing machine tub and its dolly, of a guard interposed between the bottom of the tub and the dolly and having means at the top to prevent the clothes from working in between the guard and the dolly, the walls of said guard flaring outwardly and downwardly from the upper end of the dolly and terminating in a comparatively broad base, said means and said flaring walls operating to deflect the clothes outwardly from the center of the tub toward the walls thereof and into the path of the dolly arms.

3. The combination, with a washing machine tub and its dolly and a drive shaft for the dolly, of a clothes guard interposed between said dolly and the bottom of the tub, said guard being removable from the tub and having downwardly flaring walls for contact with the clothes to direct them outwardly from the center of the tub into the path of the dolly.

4. The combination, with a washing machine tub and its dolly, of a guard interposed between the bottom of the tub and the dolly and having means to prevent the clothes from working in between the guard and the dolly, the walls of said guard extending downwardly and having their lower portion adjacent the bottom of the tub, said walls operating to deflect the clothes outwardly from the center of the tub toward the walls thereof and into the path of the dolly.

5. The combination, with a washing machine tub and a dolly for the tub, and a drive shaft for the dolly, of a clothes guard formed independently of the tub and supported upon the tub bottom between it and the dolly, said guard having walls for deflecting the clothes outwardly from the center of the tub.

6. The combination, with a washing machine tub and a dolly for the tub and a drive shaft for the dolly, of a clothes guard formed independently of the tub and supported upon the tub bottom between it and the dolly, said guard having walls for deflecting the clothes outwardly from the center of the tub, said guard being normally seated on the bottom of the tub and removable from the tub with the dolly.

In witness whereof, I have hereunto set my hand this 6th day of May, 1918.

HERMAN C. HIRSCHY.
